UNITED STATES PATENT OFFICE.

WILLIAM HUME LOGAN, OF LOUISVILLE, KENTUCKY, ASSIGNOR TO KIRKER-BENDER FIRE ESCAPE COMPANY, OF LOUISVILLE, KENTUCKY.

FIRE-ESCAPE.

SPECIFICATION forming part of Letters Patent No. 732,645, dated June 30, 1903.

Application filed April 15, 1903. Serial No. 152,751. (No model.)

To all whom it may concern:

Be it known that I, WILLIAM HUME LOGAN, a citizen of the United States, residing at Louisville, in the county of Jefferson and State 5 of Kentucky, have invented certain new and useful Improvements in Fire-Escapes; and I do declare the following to be a full, clear, and exact description of the invention, such as will enable others skilled in the art to which 10 it appertains to make and use the same, reference being had to the accompanying drawings, and to the letters of reference marked thereon, which form a part of this specification.

15 My invention relates to fire-escapes, and more particularly to that class of fire-escapes which comprise a spiral way or slide inclosed within a vertical cylinder or tower.

The object of my invention is generally to 20 improve the construction and operation of this class of fire-escapes; and with this object in view my invention consists in the improved construction or arrangement and combination of parts hereinafter fully described and 25 afterward specifically pointed out in the claims.

In the accompanying drawings, Figure 1 is 30 a perspective view of part of a fire-escape constructed in accordance with my invention, parts being broken away to more fully illustrate the construction. Fig. 2 is a detail sectional view on a horizontal plane cutting through the central support and spiral slide-way. Fig. 3 is an end view of the sheet forming the central support after the edges have 35 been bent in and before bending in the center. Fig. 4 is a detail view of the central support ready to receive the slide-way. Fig. 5 is a view similar to Fig. 2, illustrating a 40 slightly-modified form. Fig. 6 is a detail view showing the edges of the central support bent out. Fig. 7 is a horizontal cross-section thereof. Fig. 8 is a view of a modification.

Like letters of reference mark correspond- 45 ing parts wherever they appear in the several figures of the drawings.

Referring to the drawings by letters, A indicates a vertical cylinder, column, or tower, which may be erected in a building or outside

thereof and adjacent thereto in any suitable 50 manner, access being had to the interior thereof at the top or at suitable intervals by any known or approved means, the construction of the tower or the means of access to its interior forming no part of the present invention. In the interior of the tower is erected 55 a spiral slide-way B, composed of sheet metal, whose outer edge rests against the inner surface of the tower and is secured thereto in any suitable manner. The inner edge of the 60 slide-way B is secured to a central twisted support D, composed of sheet metal, prepared by first bending the edges inward, as at E, until they reach the main body, leaving 65 smooth or somewhat rounded surfaces, and then bending or doubling them upon themselves at the center, as at F, the bent or folded edges meeting, as shown. The inner edge of 70 the slide-way is placed between the folds of the central support D and secured by rivets G. It will of course be understood that the central support will be twisted to correspond 75 with the spirally-arranged inner edge of the slide-way.

In the construction shown in Fig. 4 the 75 metal of the central support D is bent or doubled upon itself at the center and then bent to form to receive the edge of the slide-way B, the folded center being placed upon the top or face of the spiral slide-way and presenting 80 a rounded edge or surface, the same as in the other form, the object being to avoid exposing a sharp edge of the central support D upon the face of the slide-way, thus insuring 85 the users of the slide-way against injury to the person or clothing by contact with such rough edges in sliding down the slide-way.

In the modification shown in Fig. 8 the inner edge of the slide-way is bent back upon itself, which sufficiently stiffens the same, so 90 that the central support may be entirely dispensed with, thus greatly simplifying the entire arrangement.

The construction and operation of the invention will be obvious from the foregoing description, taken in connection with the illustrations, and I desire it to be understood that I hold that any slight changes in the construc- 95

tion of the various parts, such as might be made by the ordinary mechanic after inspecting my invention, would be clearly included within the limit and scope of my invention.

Having thus described the construction and operation of my invention, what I claim as new, and desire to secure by Letters Patent of the United States, is—

- 10 1. In a fire-escape, the combination with a cylinder or tower, of a spiral slideway therein, composed of sheet metal, secured to the inner surface thereof, and a central support consisting of sheet metal, doubled upon itself, and then doubled over the inner edge of the slideway and secured thereto, substantially as described.
- 15 2. In a fire-escape, the combination with a cylinder or tower, of a spiral slideway therein, composed of sheet metal secured to the inner surface thereof, and a central support consisting of sheet metal, doubled upon itself, and then doubled over the inner edge of the slideway and secured thereto, the edge of the support on the one face of the slideway being

folded to form a rounded or smooth edge or surface, substantially as described.

3. In a fire-escape, the combination with a cylinder or tower, of a spiral slideway therein composed of sheet metal secured to the 30 inner surface thereof, and a central support consisting of sheet metal doubled inward at the edges and then doubled over the inner edge of the slideway presenting rounded edges upon the front and rear, or upper and 35 lower face of the slideway, and secured to said inner edge, substantially as described.

4. In a fire-escape, the combination with the cylinder or tower, of a spiral slideway therein composed of sheet metal secured to the 40 inner surface thereof, the inner edge of said slideway being folded back upon itself to stiffen the same, substantially as described.

In testimony whereof I affix my signature in presence of two witnesses.

WILLIAM HUME LOGAN.
